US0D1079959S

(12) **United States Design Patent** (10) **Patent No.:** **US D1,079,959 S**
(45) **Date of Patent:** **** Jun. 17, 2025**

(54) **CONTAINER**

(71) Applicant: **Group B Labs LLC**, Seattle, WA (US)

(72) Inventors: **Illi Eisner**, Seattle, WA (US); **Olivia Eisner**, Seattle, WA (US); **Alexei Zyuzin**, Seattle, WA (US); **Michael Kritzer**, San Diego, CA (US); **Frederick Sayre**, McKinleyville, CA (US)

(73) Assignee: **Group B Labs, Inc.**, Westport, CT (US)

(**) Term: **15 Years**

(21) Appl. No.: **29/940,879**

(22) Filed: **May 6, 2024**

Related U.S. Application Data

(63) Continuation of application No. 29/776,089, filed on Mar. 26, 2021, now Pat. No. Des. 1,026,233.

(57) **CLAIM**

The ornamental design for a container, as shown and described.

DESCRIPTION

FIG. 1 is a front perspective view of a container showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the container that form no part of the claimed design.

1 Claim, 6 Drawing Sheets
